UNITED STATES PATENT OFFICE.

HARRY B. HILLS, OF NEW YORK, N. Y., ASSIGNOR TO STEWARD DAVIT & EQUIPMENT CORPORATION, OF NEW YORK, N. Y., A CORPORATION OF NEW YORK.

DRAIN DEVICE FOR LIFEBOATS.

Application filed August 15, 1925. Serial No. 50,378.

The object of the present invention is to provide a drain device for life boats comprising a rain valve fitted into the hull of the boat and adapted to permit the draining off 5 of any water passing into the boat while the latter is inboard, as on the davits of the ship. Prior to launching the boat the valve need not be altered inasmuch as water is prevented from passing upward into the boat by an 10 automatic valve closing member. However, a cap device may be employed for furnishing an additional seal or closure for the valve at the time the boat is in service.

The invention will be understood by reference to the accompanying drawings in which—

Figure 1 is a fragmentary plan view of the bottom of a boat with the drain device installed therein, the latter being partially 20 broken away;

Figure 2 is a transverse section of the same on the line 2—2 of Figure 1;

Figure 3 is a perspective view of the flap valve member.

Referring to the drawings, it will be noted that 1 represents the hull of a boat in which the device is installed. The hull is formed with a circumferential opening 2 into which is fitted the valve casing 3, the latter being 25 formed with a wide marginal flange 3^x which is counter-sunk in the hull and secured in position by the bolts 4 and nuts 4^x. The vertical wall of the valve casing is formed with an opening 5, which opening is overhung by a horizontal wall 6 which projects inwardly and which merges into parallel inwardly projecting walls 7. Also, the bottom of the valve casing forwardly of walls 6 and 7 is open for the passage of water.

Pivottally supported within the valve casing by means of the screws 8 is a flap valve 9, which flap valve normally closes the passage-way intermediate walls 6 and 7. The base of the flap valve is preferably disposed 40 slightly above the base of the valve casing so that it will not be subject to such frictional action of the water when the boat is being propelled as to tend to rock the flap on its pivotal supports.

The exterior of the valve casing is threaded 50 to receive the projecting thread of a cap member 10 and through the cap member is

projected a screw or like stop 11. When the cap is raised to the dotted line position, Figure 1, stop 11 will meet a shoulder 11^x on the 55 valve casing and thus will prevent the cap from being removed. However, the cap may be sufficiently raised as to expose inlet 5 and permit water to pass downwardly through passageway a, thence through inlet 5 into 60 the valve casing where, by its pressure, it will open the flap valve and pass out of the boat. When the boat is placed in the water, the pressure of the latter will act upon the flap valve 9 to close the latter and prevent 65 water from entering the boat.

For convenience of assembly, I prefer to cast the valve casing with an open top and with a shoulder 12, and then, after assembling the flap valve in place to close the top 70 of the casing by means of a plate soldered upon shoulder 12.

It will be noted that the flap valve, being in vertical position, or substantially so, is 75 very sensitive to the slightest pressure of water on either side thereof so that very thorough draining of the boat may be enabled and also very firm pressure of the flap valve upon the walls of the valve casing will be caused when the boat is launched so as to 80 afford a tight seal against entry of sea water.

Having described my invention what I claim and desire to secure by Letters Patent is as follows:

A drain plug for life boats consisting of 85 a flat base member adapted to be secured to the bottom wall of a boat hull so as to be substantially flush therewith and having an upwardly projecting open top cup-like member being formed with an opening at its 90 base and a side wall opening, a lateral projection extending within the cup-like member and bounding the top of its side wall opening, said projection merging into the side wall, a flap valve having a pivotal 95 mounting within the cup-like member above the inwardly projecting wall and adapted to contact with said wall and the base, and a cap adapted to enclose the upwardly projecting portion of the device and movable to expose its side wall opening.

In testimony whereof, I have signed my name to this specification.

HARRY B. HILLS.
